UNITED STATES PATENT OFFICE

CHARLES A. MOORE, OF EDINA, MINNESOTA

REFRIGERATOR

Application filed March 19, 1930. Serial No. 437,011.

My invention relates to improvements in refrigerators, an object thereof being to provide a simple, durable, compact, unitary, efficient and relatively inexpensive refrigerator for domestic and commercial use, wherein the air is refrigerated and circulated in a convective and diffused manner and wherein novel provision is made for ventilation.

Another object of the invention is to provide a structure of the present character wherein a harmless refrigerating medium is caused to be circulated by gravity through a refrigerating element within the refrigerator proper.

With the foregoing and other objects in view, which will appear in the following description, the invention resides in the novel combination and arrangement of parts and in the details of construction hereinafter described and claimed.

Fig. 1 is a vertical sectional view of a refrigerator embodying my invention, the same being taken on the line 1—1 of Fig. 2; Fig. 2 is also a vertical sectional view, the same being taken on the line 2—2 of Fig. 1 and Fig. 3 is a horizontal sectional view taken on the line 3—3 of Fig. 1.

Reference being had to the drawings, it will be seen that my improved refrigerator includes a cabinet A forming a provision chamber B, the cabinet comprising a bottom 10, front 11, back 12, ends 13 and top 14, said parts being insulated as at 15 and lined within, as by a lining 16. The front 11 of the cabinet is provided with doors 17 which lend access to the interior of the chamber B. Within the upper portion of said chamber centrally thereof are two spaced refrigerating elements C of suitable design such as that illustrated, which may comprise a conduit 18 through which a refrigerating liquid may gravitate, said conduit having a coiled portion jacketed as at 19.

Surmounting the cabinet A is an externally insulated tank D containing a refrigerating liquid such as brine. In this tank is a coil 20 and surmounting the tank is an appliance E, which may be of any conventional design, for supplying the coil 20 with

a circulating refrigerating medium, such as ammonia.

The turns of the coil 20 are banked to provide a clear vertical, central space F in the tank D (Fig. 2) and clear, vertical, side spaces G between the coil reaches and the front and rear sides of said tank. Extending along the bottom of the tank, and communicating from end to end thereof with the interior of the tank is a feed terminal 21 and two return terminals 22, the feed terminal being disposed in the central space F in the tank D and the return terminals in the outer spaces G, one in each of said two spaces. The coiled conduits 18 of the refrigerating elements C are connected with the feed and return terminals 21 and 22, the extremity 18^a of each conduit, which feeds into the upper portion of the coiled portion thereof, communicating with the feed terminal 21 and the other extremity 18^b of each conduit 18 communicating with one of said return terminals 22.

The brine or other fluid in the tank D, being cooled by the refrigerating medium in the coil 20, circulates by gravity through the conduits 18 of elements C, thus causing the chamber B and its contents to be refrigerated. This refrigerating fluid being of such character as brine and consequently having no possible deleterious effect upon the edible contents of the chamber renders the refrigerator entirely safe in use.

Owing to the form of the coil 20 and its disposition within the tank D and to the superimposed relation of said tank with respect to the refrigerating elements C, an effective gravitating circulation of brine is set up within the tank D and a like circulation set up in said elements C, from said tank D, through conduits 18, and back to the tank. In the tank, the brine in the central space F, where it is relatively cold, flows downward to bottom of the tank, thence divides and flows in opposite directions to the spaces G, where it ascends along the relatively warm front and rear walls of said tank. Thence, the brine flows inwardly to the central space F, thus completing the cycle. With the feed terminal 21 at the bottom of the central

space F and at the point of lowest temperature in the tank; the brine at such locality readily gravitates into said terminal 21 and from it through the extremities 18^a of conduits 18 to and through the coiled portions 5 thereof. With the return terminals 22 at the bottom of spaces G, where the flow of brine is in an upward direction, the return flow of the brine through the extremities 18^b of the conduits 18 is enhanced. Thus, there is 10 a definite gravitating circulation of brine within the tank D and from the tank to the refrigerating elements C and back again to the tank.

The refrigerating elements C occupy position within a bunker structure H spaced from the ends of the chamber B and extending from front to back thereof. This bunker structure comprises hollow baffles 23, 24 preferably formed of sheet metal, each baffle consisting of a side member 25 and a bottom member 26, the same communicating with each other. The bottom members 26 of the baffles 23, 24 are spaced apart at their 25 adjacent inner extremities to form a central air egress port 27, while the side members 25 of said baffles are spaced at their upper extremities from the ceiling of the chamber B to provide passageways 28 for the passage 30 of air from the upper portion of the chamber B into the upper portion of the bunker structure. The interior of the hollow baffle 23 communicates at the upper portion of its side member 25 with the outer air through a fresh air ingress pipe 29 in the back of the cabinet A, the inner edge of the bottom member 26 of said baffle 23 being open along 35 its extent to provide an outlet 30 for the egress of air from said baffle into the chamber B at the port 27. The interior of the hollow baffle 24 communicates along the upper edge of its side member 25, through an ingress opening 31 with the chamber B at the passageway 28 between said side member 25 and the ceiling of the chamber. The bottom member 26 of this hollow baffle 24 40 communicates at the inner portion thereof with the outer air through an egress pipe 32 in the back of the cabinet.

45 The air within the chamber B circulates chiefly as follows: That air within the bunker structure H and about the refrigerating elements C, being cooled in greatest degree descends through port 27 falling to the floor of the chamber B. At this point the stream 50 of air is divided, whence it flows in opposite directions toward the relatively warm ends of the chamber, and thence ascends along said ends to the ceiling. Thence, the air flows in- 55 wardly through the passageways 28 over the refrigerating elements C, where the cycle is begun anew. In its travel the air passes through shelves 33 suitably arranged and of 60 suitably meshed material, the same moving 65 about the various commodities placed on said

shelves. Thus, a convective and diffused circulation of refrigerated air is established within the chamber B, whereby the refrigerator is rendered efficient in maximum degree.

70 A secondary ventilating circulation of air, by gravity, is set up within the device as will now be described. The sheet metal shells forming the baffles 23, 24 are, of course, affected by the refrigerating elements C, the air within the interior of each being reduced in temperature as compared with the temperature of the air outside of the cabinet. Air gravitating through egress pipe 32 from the interior of baffle 24 establishes a scavenging flow from the upper portion of the chamber B, the air from that locality entering the baffle 24 through opening 31 at the passageway 18 formed between the side member 25 of said baffle and the ceiling of the chamber. Air gravitating into baffle 23 through ingress pipe 29 flows from the outlet opening 30 in said baffle, joining the circulating flow of air within the chamber B at the port 27. Thus, it will be seen that the circulating flow of air within the chamber and the ventilating flow of air cooperate, the one aiding the other in movement by gravity.

75 Dampers (not shown) may be suitably arranged to control the flow of air through either or both of the hollow baffles 23, 24, whereby the user of the refrigerator may modify or entirely arrest the ventilating circulation of the air.

80 The bottom members 26 of the baffles 23, 24 catch any drip from the refrigerating elements C and also condensation that may form on the baffles, said bottom members being sloped, as shown, and perforated as at 85 (Fig. 3), to drain into branch drain pipes 35, 105 which meet at the lower portion of the chamber B and form a single drain 36.

85 Changes in the specific form of my invention, as herein disclosed, may be made within the scope of what is claimed without departing from the spirit of my invention.

90 Having described my invention, what I claim as new and desire to protect by Letters Patent is:

95 1. In a refrigerator, a cabinet providing a 115 chamber for provisions and having a door lending access to the chamber, a tank containing a refrigerating liquid superimposing the cabinet, a coil in the tank for a circulating refrigerating medium, means superimposing the tank for supplying such medium to the coil, said coil being arranged to provide a clear vertical space between it and a side wall of said tank, a refrigerating element in the provision chamber comprising a 120 conduit for the circulation of the refrigerating liquid therethrough, a feed terminal and a return terminal extending along the bottom of the tank and communicating from 125 end to end thereof with the interior of the 130

5 tank, the feed terminal being disposed beneath the coil and the return terminal disposed in said vertical space adjacent said side wall of the tank, the conduit of the refrigerating element communicating with the feed terminal and with the return terminal.

10 2. In a refrigerator, a cabinet providing a chamber for provisions and having doors at the front thereof lending access to the chamber, a tank containing a refrigerating liquid superimposing the cabinet, a coil in the tank for a circulating refrigerating medium, means superimposing the tank for supplying such medium to the coil, said coil being arranged to provide clear vertical spaces between it and the side walls of the tank and to provide a clear vertical central space within said tank, a pair of spaced refrigerating elements disposed centrally of the provision 15 chamber in the upper portion thereof, each comprising a conduit for the circulation of the refrigerating liquid therethrough, a feed terminal and return terminals extending along the bottom of the tank and communicating from end to end thereof with the interior of the tank, the feed terminal being disposed in said central space and the return terminals disposed in said outer spaces, respectively, the conduit of each refrigerating 20 element communicating with the feed terminal and with one of said return terminals.
